UNITED STATES PATENT OFFICE

2,016,086

APPARATUS FOR COOLING LIQUIDS

Ernest F. Fisher, St. Louis, Mo.

Application June 11, 1934, Serial No. 730,163

18 Claims. (Cl. 261—79)

The present invention relates to an apparatus for evaporating and cooling liquids and more particularly to apparatus for removing heat from water that has been used in condensing or cooling systems having application to refrigeration, the cooling of internal combustion engine cylinders and the like, the cooling of liquids and gases, cooling systems for homes, offices and public places and other applications where water is used over and over again for transferring heat in process work.

One of the principal objects of my invention is to provide a cooling system employing air in intimate contact with water to be cooled so as to evaporate a part of the water and in so doing lower the temperature of the water to near the wet bulb temperature of the atmosphere, it being obvious that the temperature of the water cannot be reduced below the wet bulb temperature. A modified form of my invention contemplates an efficient means for condensing gas to a liquid.

Another object of my invention is to provide an improved method and means for circulating the cooling air in conjunction with the water and in a counterflow manner.

Another object is to provide a cooling tank comprising a series of sections adapted to be grouped in a nested form to facilitate shipment.

Other objects will be apparent from the specification which follows.

As the effectiveness of the apparatus as herein-after described is dependent upon its ability to evaporate large amounts of water, the apparatus can be used as a humidifying machine. It can also be used as a gas and air washer.

In the accompanying drawings which show a diagrammatic representation of a preferred embodiment of my invention and various modifications thereof:

Figure 1 is a vertical sectional view of a preferred form of my invention;

Fig. 2 is a sectional view on line 2—2 of Figure 1 in the direction of the arrows;

Fig. 3 is a vertical sectional view of a modification;

Fig. 4 is a vertical sectional view of another modification;

Fig. 5 is a partial view in side elevation of the device of Figure 4;

Fig. 6 is a sectional view taken on line 6—6 of Figure 4;

Fig. 7 is a vertical sectional view of a further modification; and

Fig. 8 is a sectional view on line 8—8 of Figure 7.

This application is a continuation in part of my application, Serial No. 623,898, filed July 21, 1932, and allowed July 7, 1933.

Referring to Figures 1 and 2 of the drawings, I have shown an assembled cooling tank formed of

a plurality of sections. The lowermost section 1 forms a reservoir for collecting the cooled liquid. The intermediate section 2 provides an air inlet and mixing chamber. A series of upper sections or auxiliary mixing chambers 3, 4, 5 and 6 are arranged above section 2 and are formed to communicate with each other in a manner to permit air and liquid to flow therethrough axially. The uppermost chamber 7 functions primarily as an eliminator chamber.

It will be observed that the diaphragms 8, 9, 10, 11 and 12 rest on a beading rolled in the walls of sections 2, 3, 4, 5 and 6, to form joints between the sections and each joint is sealed against the exit of water and air by means of a packing of tar or cement 13 to provide a water tight diaphragm between adjacent sections except at a central orifice in each diaphragm.

The liquid to be cooled is pumped into the cooler through a conduit 14 which terminates in a spray head 15. A diaphragm 16 forms the bottom of section 2 and has a central passage 17 for cooled liquid. A conical member 18 is positioned centrally of section 2 being secured to the diaphragm 16. The conduit 14 preferably passes axially through this member. Openings 19 around the lower periphery of this member permit liquid to flow from chamber 2 through passage 17 to reservoir 1. An air inlet is arranged tangentially to the wall of section 2 in a manner to cause air forced thereto to swirl close to the wall of this section and towards its axis up to the member 18. A spiral vane 21 is arranged on conical member 18 in order to guide the air swirl more effectively upwardly. The purpose of the member 18 is to cause the formation of a cyclonic swirl in the air supplied from the inlet 20. Each diaphragm 8, 9, 10 and 11 has a central opening and the metal adjacent the periphery of each opening is bent downwardly and formed with serrations 22. The diaphragms 9, 10 and 11 have suspended therefrom an auxiliary diaphragm or baffle plate 23, 24 and 25, each likewise having a central opening and serrations 22. The openings in these diaphragms increase in diameter upwardly.

The section 7 is provided with an outlet 26 and a series of eliminator plates 27 which function to separate particles of liquid from the air leaving this outlet, which liquid is permitted to flow inwardly to remain within the cooling tank. A liquid outlet conduit 28 serves to permit withdrawal of cooled liquid.

In operation, cooling air is forced inwardly from inlet 20 in a manner to swirl around the conical member 18. This air is forced into a cyclonic swirl and is directed upwardly by member 18 and vane 21 through all central openings in the various diaphragms. Liquid to be cooled is sprayed from the head 15 into sections 4, 5, 6 and 7. This spray is intimately mixed with the

air passing upwardly. This liquid spray collects on the diaphragms and flows from each diaphragm onto the diaphragm just below. This liquid flow is broken up into small streams by 5 means of the serrations 22 to provide a more intimate mixing of liquid and air during counter-flow of these streams.

The orifice 22 in the lowermost diaphragm 8 is flared outwardly so that the water falling off 10 its serrated edges will fall in the path of the high velocity air before the air is converged by cone 18. In this manner, the water is not permitted to fall on cone 18 at which point the air has a low velocity. The outer zone of the swirl 15 constitutes an area of high peripheral velocity which velocity decreases as the air converges for entry to the lower orifice but the linear velocity increases. The highest velocity of swirl or the peripheral velocity is at the serrated edges where 20 the water leaves the diaphragms in droplets. The air swirl keeps the water on the diaphragms and will not permit the water to fall down through the center of the orifices. These orifices of the diaphragms increase in diameter upwardly so as to 25 increase the velocity of swirl of air upwardly and to cause the air to expand.

The modified device of Figure 3 is in all respects similar to that of Figure 1 except that a plate 29 is suspended by hangers 30 from the 30 diaphragm 8 and, in turn, supports the conical member 18. The plate 29 serves the same purpose as the flared central orifice in diaphragm 8 in Figure 1. The cone 18 increases the velocity 35 of swirl and converges the air for entrance into the orifice 31. The water falls through this orifice onto the plate 29 which is comparatively large in diameter and the edge of this plate from which the water falls lies in the path of the high velocity air which breaks the water up into a 40 fine spray.

In Figure 4, the cooling tower is formed from a reservoir section 32, a swirl or inlet chamber 33 and a series of mixing chambers 34, 35 and 36. A cone 37 is suspended inverted from a diaphragm 45 38 which has a central orifice 39 fringed with serrations 40. The cone 37 is made up of vanes 41 a cross section of which is shown in Figure 6. The edges of these vanes are set at a slight angle with the body portions thereof twisted or warped 50 as shown in Fig. 4, so that they cut the air swirl. Other diaphragms 42 and 43 formed similar to diaphragm 38 serve to support cones 44 and 45 which are similar to cone 37. A tangential air inlet 28 is provided in line with cone 37. Water 55 to be cooled is sprayed in from a spray head. An air outlet 47 is provided with liquid eliminator plates 48. The cones 37, 44, 45 are located in the vortex of the air swirl and serve to guide the water discharging from head 46 into the vortex where it is further broken up as it falls through 60 each succeeding orifice. The eliminator plates 48 prevent fine spray from discharging from outlet 47.

In operation, air enters through inlet 28, swirls 65 around cone 37 and is cut by vanes 41. This air swirl continues upward through each cone 44, 45, and out through outlet 47. Water that falls through the central orifices must fall through the cones in the path of the vortex, thus being broken up into spray.

The modification of Figures 7 and 8 relates to an apparatus for more efficiently condensing gas to a liquid as applied to refrigeration machines 70 or to cool the water that is circulated through

Diesel and other internal combustion engine jackets.

According to the present practice in refrigeration, the water is cooled in a cooling tower and then pumped through the condenser. This procedure involves two distinct steps and the cost of pumping is sometimes high due to friction head through the condenser. In this indirect process, there is a considerable loss in heat transfer efficiency.

In Figure 7, a coil 49 in which the gas to be condensed is compressed, is located in the path of the cooling air and water. This coil is formed as two spaced spirals between which the air and water may pass to contact all coil surface. This 10 coil is located within the cooling tower which 15 comprises a series of sections 50, 51, 52, 53 and 54 constructed similar to the sections shown in Figure 1, whereby the sections, when not assembled, may be nested. Sections 51 to 54 each terminate 20 at one end in a diaphragm 55 which is provided with a central orifice 56 fringed with serrations 57. Lower section 50 serves as a reservoir to receive the spent cooling water. A cone 58 is secured to the bottom wall of the reservoir and 25 extends axially within the tank well past the air inlet 59 which extends tangentially into the tank as shown in Figure 8. Cooling water is supplied from conduit 60 which terminates in a spray head 61, and the spent sprayed water may collect in 30 reservoir 50. If desired, the conduit 60 may draw water from reservoir 50 and make up water to supply loss due to evaporation may be supplied from a conduit 62 to the reservoir and the water level controlled by a float valve common to this 35 art. Gas to be condensed is supplied to coil 49 by an inlet pipe 63 and this gas, when condensed, will drain through a pipe 64 to a receiver 65. Eliminator plates 66 in air outlet 67 serve to remove all water particles from the outgoing air. 40

In operation, the air enters the inlet 59 and swirls around at high velocity in chamber 51 and threads its path upwardly to outlet 67. The cone 58 serves to increase the velocity of swirl of the air keeping the water from spray head 61 in contact with the coils 49. The diaphragms 55 fit close to the spiral coil and prevent any spray from passing unless it contacts the coil and air swirl. This results in maximum evaporation on the surface of the coil, thus cooling the coil and extracting the heat from the compressed gas 50 which is liquefied and passed out through conduit 64. A blower, not shown, serves to force air into inlet 59.

When the device of Figure 7 is applied to Diesel 55 engine cooling, the coil 49 forms a closed circuit with the engine jacket and pump, which circuit is filled with pure water that will not form scale. Very little evaporation occurs in this closed circuit as the water does not contact the cooling air. 60 The water used in the cooling tower as a spray may be of lesser purity.

It will be noted in the various modifications shown that a conical member is arranged adjacent an air inlet and this air is caused to swirl 65 around in the chamber containing the cone and the cone acts with the air inlet to produce a cyclonic swirl which is directed upwardly to pass through the orifices in the diaphragms. The liquid spray flows downwardly through each 70 orifice and from the edge serrations in a manner to intimately mix with the cooling air. Other features are common to the various modifications.

The various modifications shown are intended 75 to illustrate preferred forms of my invention, but

it is to be understood that other modifications and variations are contemplated such as will be embraced within the scope of the following claims.

What I claim is:

5 1. In a cooling and evaporating apparatus comprising a vertical tank, said tank having a tangential air inlet, a cone disposed axially in said tank and opposite to said air inlet, a diaphragm disposed above the cone and having a hole in its center, said hole being in line with the apex of said cone, a second diaphragm disposed above said first diaphragm and being provided with a hole in its center in line with the hole in the first diaphragm, said diaphragms forming compartments within said tank and effectually preventing water and air from passing said diaphragms save through the relatively large holes in their centers through which air is adapted to pass in a cyclonic swirl upwardly from said cone, and means to spray liquid into the upper end of said tank.

2. In a cooling apparatus comprising a vertical tank, a conical member positioned centrally of said tank, an air inlet to said tank positioned substantially in the plane of said member and tangentially thereto and to the wall of said tank, means for forcing air into said inlet and around said member whereby said conical member will produce a cyclonic whirl within the tank, a series 30 of transverse partitions within said tank secured in a water tight manner along their outer edges to the wall of said tank and spaced at different distances above the conical member, each partition having a relatively large central orifice through which swirling air may pass upwardly from said conical member the apex of the conical member being directed towards the central orifices to direct air thereto.

3. In a cooling apparatus as set forth in claim 2, means for spraying liquid to be cooled to said tank to mingle with the swirling air.

4. In a cooling apparatus as set forth in claim 2, the edge of each orifice being provided with a series of downwardly projecting points, and means for spraying liquid to said tank to mingle with the swirling air.

5. In a cooling apparatus as set forth in claim 1, wherein the cone is hollow and is provided with openings through its wall for permitting fluid to flow therethrough into the cone, a diaphragm to support said cone, and a fluid orifice formed in the cone supporting diaphragm below said cone.

6. In a cooling apparatus as set forth in claim 2, means for spraying liquid to be cooled to said tank to mingle with said air, a transverse wall for supporting said cone, a liquid reservoir below the transverse wall, said conical member and wall being provided with openings for passing liquid therethrough to said reservoir.

7. In a cooling apparatus, a vertical tank, a series of transverse diaphragms secured in a water tight manner along their outer edge to the wall of said tank providing compartments, each diaphragm being provided with a central orifice, a baffle plate secured directly to each diaphragm and spaced therefrom and from the wall of the tank, each baffle plate having a central orifice, all of said orifices being coaxial and decreasing in diameter downwardly.

8. In a cooling apparatus as set forth in claim 7, wherein certain of said orifices along the edges thereof are provided with a series of downwardly projecting points.

9. In a cooling and evaporating apparatus, a tank comprising a plurality of sections adapted to be assembled in concentric axial alignment, the cross sectional area of the sections decreasing relatively in one direction when in assembled relation, said sections being formed similarly whereby to be assembled in a nested relation as a compact unit prior to their assemblage as a tank certain of the sections having a transverse member, each member having a central opening there-through, the edge of each opening being bent to form a flange.

10. In an apparatus as set forth in claim 9, the opposed adjacent ends of each pair of sections being formed to permit telescopic engagement thereof during assemblage to form a tank.

11. In an apparatus as set forth in claim 9, the opposed adjacent ends of each pair of sections being formed to permit telescopic engagement thereof during assemblage to form a tank, and means on one adjacent section for limiting the amount of telescopic overlap while in assembled relation.

12. In an apparatus as set forth in claim 9, certain of said sections being provided with a transverse member at one end, each said member having a central opening, said openings being aligned axially when the sections are assembled.

13. In an apparatus as set forth in claim 9, one of said sections being provided with a tangentially arranged air inlet, and a conical member positioned centrally of said member to be impacted with air from said inlet to form a cyclonic swirl and direct same along the axis of said section.

14. A cooling apparatus comprising a tank, a coil for receiving material to be cooled arranged spirally axially of said tank, an inlet for forcing cooling air into said tank adjacent an end thereof, a conical member positioned within said coil, said inlet being arranged tangentially to said member whereby the member causes cooling air to flow axially up the coil, and means to spray a liquid into said tank to contact said coil and pass therethrough in counterflow to said cooling air.

15. In a cooling apparatus comprising a main chamber, a series of transverse members positioned to divide said main chamber into a plurality of chamber sections, said members each being formed to provide an opening centrally therein, a plurality of spaced elongated members each secured at one end in spaced relation to each transverse member adjacent the edge of the opening therein, said elongated members being extended downwardly and inwardly substantially to form a conical shape.

16. In a cooling apparatus as set forth in claim 15, wherein the edge of each transverse member that defines the opening is formed to provide a plurality of laterally offset serrations.

17. In a cooling apparatus as set forth in claim 15, wherein each elongated member is formed to provide a warped surface.

18. In a cooling apparatus as set forth in claim 15, an inlet conduit opening into the chamber adjacent the bottom thereof and arranged tangentially thereto and in the plane of the lowermost group of elongated members whereby fluid admitted through the inlet is caused to impact said members during its passage upwardly through the openings.

ERNEST F. FISHER.
